UNITED STATES PATENT OFFICE.

ALBERT H. HENDERSON, OF BALTIMORE, MARYLAND, ASSIGNOR TO THE HENDERSON RUBBER COMPANY, OF BALTIMORE, MARYLAND, A CORPORATION OF MARYLAND.

ARTICLE OF MANUFACTURE.

1,215,275.

Specification of Letters Patent.

Patented Feb. 6, 1917.

Application filed January 13, 1912. Serial No. 671,045.

To all whom it may concern:

Be it known that I, ALBERT H. HENDERSON, a citizen of the United States, residing at Baltimore, State of Maryland, have invented new and useful Improvements in Articles of Manufacture, of which the following is a specification.

My invention relates to an article of manufacture designed to have great strength, 10 tenacity and elasticity together with the minimum of thickness and weight, it being intended for use in any of the industrial arts wherein it is applicable, but more especially as a body, filler, lining or element in 15 tires adapted for automobiles, motor-cycles or ordinary vehicles.

In carrying out my invention I employ a fibrous body or material which has been mercerized, and which is formed with a special weave or braid on the bias at a suitable angle. This weave or braid may be single or multiple, its system of diagonal weft or wefts as seen in cross section having the effect of preventing breakage due to the 25 strain in the direction of the article or upon the threads in the direction of their length. The phrase diagonal weaving or braiding is intended to apply to a type of mercerized fabric including bias or angular weaving or 30 braiding, the direction thereof on opposite sides being in reverse. Thus my mercerized fabric is dissimilar from mercerized fabrics or cloths woven in the straight or ordinary way. This improved fabric may be woven, 35 knitted, or braided diagonally at the desired angle in cross section and used in the form of a cloth or a tubing, and has great strength, tenacity and elasticity. For example, in its tubular form compensation is 40 provided for under variations in strain, pressure or motion, lateral or otherwise.

My invention is more especially directed to a back and face fabric of the same material and of the character above outlined. 45 The advantages of a mercerized fabric over one unmercerized are important. On account of the chemical treatment to which it has been subjected, the mercerized fabric is strengthened, made more absorbent and 50 more flexible than one unmercerized. It is also thinner and lighter for a given strength, and has greater durability and toughness, the increase in strength of a mercerized fabric over one unmercerized of the same 55 original fibrous character being from five to

fifteen times. It is peculiarly adapted to my present purpose for, inasmuch as the oils, wax, gums, etc., are removed, a porous fiber is left which offers the best possible surface and interior for rubber treatment. 60 Such mercerized fabric is to a marked extent uniform in character, whether as to the individual fibers or as to the weave as a whole and, its fibers being smaller than those of a fabric not mercerized, a greater number 65 can be put in the same space than is practicable with unmercerized fibers. It follows that the woven or braided mercerized material offers a greater fiber surface for the absorption of or incorporation or 70 union with rubber, and this is true of the surface as well as the interior of the fiber. The interior of each fiber when mercerized forms a cylindrical receptacle, and to this the rubber incorporated with the fabric 75 reaches. Therefore not only is the exterior of each fiber coated, but the interior of each is filled with rubber, as also are the interstices existing between the juxtaposed fibers. Such advantages are not possible with cloths 80 simply coated with rubber, as, for example, where the latter is heated and spread or pressed upon the surface of the cloth. Nor is it possible with fabrics composed of 85 other fibrous and flexible bodies and adhesive and vulcanizable materials.

Under my invention the rubber receives the friction in the continual displacement, 90 relatively speaking, of one fiber with respect to the other in such a movement as would occur were this fabric employed in the manufacture and use of wheel tires. Furthermore, the interior of each filament or fiber of the thread being filled with rubber, there 95 can be no such collapse or flattening of the fiber, as would be the case were it unmercerized due to compression in the rotation of the wheel, and especially to the jolting, 100 sidewise movement or skidding to which tires are exposed. In other words, instead of friction occurring between the fibers themselves, and in each individual fiber between what may be termed its respective 105 walls, the friction is changed to one between interior fillings of vulcanized rubber and the inner walls of the fiber and also between the thin covering of vulcanized rubber found upon the exterior of each individual fiber. Therefore, when the whole 110

weave or braid has been mercerized and impregnated with rubber there is no friction between the natural fibers, but between fibers interiorly filled and exteriorly coated with rubber and constituting the entire fabric.

The purpose of the diagonally and reversely directed weave, or the diagonally and reversely directed interlocked weave in multiple, whether the fabric be straight or 10 circular, is to adapt it to most effectively receive the rubber deposited on the exterior of each fiber, so that the friction to which the rubber, and not the fiber, is subjected shall be distributed throughout the entire 15 fabric in the least destructive manner.

It is known that one of the important objects in the construction of a cushion tire (with which article my invention may be illustratively described) is that while it 20 shall retain its strength and flexibility it shall be consolidated as far as practicable by the permanent adhesion of its parts so that separation thereof under the various conditions to which a tire is subjected is 25 prevented. Of such conditions are concussion due to the ordinary rolling motion, or under lateral, twisting, buckling or knuckling strain, or under the jarring in a variety of directions consequent upon the 30 meeting of the tire with obstructions. In order to provide in a measure for such conditions the mercerized fabric of multiple cross ply and impregnated with rubber is used. But with this I preferably employ a 35 rawhide body or equivalent natural product of the animal kingdom, said body or product being rendered permanently spongy the open pores of which are also impregnated or saturated with rubber. These two rubber 40 saturated bodies are consolidated under heat and pressure and vulcanized, the vulcanization being effected either during the act of consolidation or at another stage of the operation. This consolidated body may also 45 be used with other and ordinary fabrics as may be desired in the formation of the tire. The rawhide is treated preferably as set forth in my Patent No. 1,020,498, dated March 19, 1912, and which mode of treatment forms no part of my present invention, 50 nor does the composition of matter the resultant of that method as set forth in my Patent No. 1,020,497 of the same date except as an element in combinations hereinafter described. It may, however, be briefly 55 stated that the rawhide is treated in the form of disks or slugs, or in fragmentary, shredded or granulated condition, in such manner as to permanently expand the hide to considerably beyond its normal state and open its pores, and thereafter impregnated with rubber whereby it is made permanently flexible or resilient. Heretofore, rawhide 60 has been softened or swollen by a steaming or hot water treatment, but such practice 65

has the disadvantage of introducing into the rawhide a certain amount of water which, penetrating to the interior of the substance and there remaining, prevents the subsequent introduction of oils or oily substances 70 or rubber solutions; and if the rawhide thus subjected to such softening and swelling treatment is afterward dried out, it resumes its original condition without any useful result having been accomplished. But as the 75 agent employed by me for the swelling and the opening of the pores of the rawhide may be removed the substance is still left substantially in the form of a spongy mass and in ideal condition to absorb any solution of 80 rubber or oily or other material which it is desired to add to the substance in order to give to it the characteristic of flexibility or resiliency. This feature of my invention will be recognized as applicable to tires, inasmuch as the combined tube used therewith, and made in accordance with my invention, 85 has all the tenacity of rawhide and the flexibility of rubber to which are added the advantages pertaining to the use of the mercerized fabric the individual fibers of which are not only charged with rubber, but the interstices existing between the fibers, or the fibers of a multiple ply are also completely 90 filled with rubber. The strength of such a combination of bodies when consolidated under heat and pressure, and the rubber has been vulcanized, forms a material for a tire which while being substantially proof 95 against puncture, is, because of the elasticity 100 found in the body, self-sealing.

In the accompanying drawings,—

Figure 1 shows in longitudinal section the spongy rawhide body not impregnated with rubber. Fig. 2 shows in similar section the 105 spongy rawhide impregnated with rubber. Fig. 3 is a plan view of a piece of mercerized fabric having the diagonal and reversely directed weave. Fig. 4 is a similar view showing the mercerized fabric impregnated with rubber. Fig. 5 is a longitudinal section of Fig. 3, showing the multiple ply, and Fig. 6 is a similar section of Fig. 4, showing the multiple ply and rubber impregnation. Fig. 7 is a longitudinal section 110 showing a consolidation of the rubber-impregnated rawhide of Fig. 2, and the rubber-impregnated mercerized fabric of Fig. 6. Fig. 8 shows the same consolidation reinforced on the underside by heavy fabric or 115 other bodies and an under layer of rubber-impregnated mercerized fabric. Figs. 9, 10, 11 and 13 show on enlarged scale forms of the mercerized fabric having diagonal and reversely directed and interlocked weave in 120 multiple. Fig. 9^a is intended to illustrate by contrast a peculiarity in my improved weave as hereinafter pointed out. Fig. 12 is an end view showing a form of circular 125 braiding in which multiple and interlocked 130

plies of the mercerized fabric are employed. Fig. 14 is a plan view of a mercerized fabric made in accordance with my invention. Fig. 15 is a plan view of such a braid as may be used in the manufacture of my improved braided fabric, the view showing cams of ordinary character. Fig. 16 shows the relative arrangement of cam grooves necessary to produce a fabric similar to that shown in Fig. 10. Fig. 17 shows a relative arrangement of cam grooves designed to produce the fabric shown in Figs. 11 and 12. Fig. 18 is a developed arrangement similar to that shown in Fig. 17 calculated to produce a straight fabric such as that shown in Fig. 11. Fig. 19 is a perspective view partly in section illustrating the use of materials entering into my article of manufacture in the construction of a wheel tire. Figs. 20, 21 and 22 show modifications illustrating the further adaptability of my improved composition of matter to the manufacture of tires.

Referring to Fig. 1, the body of rawhide 1 is shown as brought to a spongy or porous condition under the treatment hereinbefore described and ready to be impregnated with rubber. The spongy or porous character of the rawhide is indicated by 2, and as shown in Fig. 2 the rubber 3 is caused to fill all the interstices, the exterior surfaces of the body being also coated with rubber. A product of great strength, toughness and elasticity is thus made. In Fig. 3 the fibrous body or material hereinbefore described as mercerized is shown by 4, its special weave or braid 5 being diagonal, the fibers standing at an angle of 45 degrees more or less and interlacing or crossing. The ply may be single or multiple, Fig. 5 showing the reversely directed plies in multiple. Whether the plies be single or multiple, the interstices existing between the juxtaposed fibers are filled with rubber, and the exterior surfaces of the body coated with rubber, which features are indicated in Fig. 4 wherein, as also in Fig. 6, the rubber is shown by 3. This treatment of the mercerized fabric, especially when in multiple ply, also produces a body of great toughness and resiliency. The diagonal weave, crossed as stated, especially qualifies the rubber treated mercerized fabric to be intimately united with the rubber-treated rawhide; for on consolidation being effected the interlocking of the crossed diagonal weave with the rubber-treated rawhide is such as to create an immovable joint incapable of lateral or other dislodgment, the pressure applied being such as to impress the crossed weave firmly into the rubber coating of the rawhide and even into the hide itself.

In order to give a fuller understanding of the expediency of manufacture and utility of my improved woven or braided fabric, I

have shown in Figs. 9, 10, 11, and 13, forms of multiple straight weave in which the system of the diagonally directed, crossed and interlocked threads found operative and advisable are illustrated; while in Fig. 12 an equivalent system is utilized in a circular braid.

Figs. 9, 10, 11 and 13 are sectional views taken on the diagonal lines indicated in Fig. 14.

In Fig. 9 a form of double-ply straight weave or braid is shown. In Figs. 10 and 11 the ply is triple as it is also in Fig. 12, the latter showing a circular braid. In Fig. 13 the fabric is four-ply and straight.

The purpose of the diagonally and reversely directed weave, or the diagonally and reversely directed interlocked weave in multiple, whether the fabric be straight or circular, is to adapt it to most effectively receive the rubber deposited on the exterior of each fiber, so that the friction to which the rubber, and not the fiber, is subjected shall be distributed throughout the entire fabric in the least destructive manner.

By referring, for example, to Fig. 10, it will be seen that the warp 1 being interlaced with the central weft of the three ply structure, the strain upon the yarn is relieved and breakage thereof from undue tension prevented. The same advantages are found in such a structure of fabric as is seen in Figs. 11, 13 and 12. In Fig. 9, the fabric being but two-ply, the same degree of undue tension placed upon the warp as occurs in Figs. 10, 11, 13 and 12, is not found. In Fig. 9^a is illustrated a structure of fabric which is not a part of my present invention, inasmuch as there is not a carrying of the warp from the face to the back of the fabric and an interlacing of the warp with an intermediate weft.

The advantage of giving to the warp and weft a crossed or angular relation to each other, as shown by 4, 5 in Fig. 3, whereby is produced what is termed herein a diagonal weave, is that a closer weave can be obtained from such classes of yarn as may be used in a straight weave, that is to say, one in which the warp and weft run at right angles to each other. This advantage obtains, and to a greater degree, when this crossed or angular relation is given to plies in multiple as seen in Figs. 9, 10, 11, 13 and 12. It will be seen that in the special weave herein described and shown a multiple ply fabric is produced of the same material having a series of warps which pass from the face to the back and which in so passing interlace with intervening wefts, this course of interlacing being repeated throughout the entire pattern. While with a straight weave in which the warps and wefts are interlaced as herein described, blow holes in the rubber with which it is intended to be impregnated

are not generally found, this is especially true of the diagonally woven fabric in which the possibility of blow holes occurring is reduced to a minimum. In other words, the fabric of this reversely and diagonally woven type when treated with rubber can be consolidated into a mass the compactness of which, it is believed, is not known to the prior art, adapting my fabric to withstand great strains and stresses, as in automobile tires, fire hose and the like in which great stability, durability and solidity, due to this compactness, are required.

The passage of the warp from the face to the back of the pattern, and the interlacing of the warp with the intervening weft greatly increases the strength of the fabric, especially against tensional strain, even when the fabric is not combined with rubber. But the strength of the article is largely increased and its fitness for commercial uses enhanced when the fabric is charged internally with rubber and the latter is externally locked by the anchorage afforded by the face and back course of the warp and the interlacing thereof with the intervening weft.

The article of manufacture thus far described may be used alone in the arts, and especially in the manufacture of cushion tires; but as shown in Fig. 8 the rubber impregnated or treated rawhide and the rubber saturated mercerized fabric, joined as stated, and as shown in Fig. 7, are reinforced, preferably upon the inner side, with bodies of heavy fabric shown by 6, and by an under layer of mercerized and rubber impregnated fabric as indicated by 4^a, the whole being consolidated under the influences of heat and pressure. The purpose of the interposition of the heavy fabric 6 between the two layers of rubber treated mercerized fabric is to increase the stiffness of the whole composition where too much elasticity might be objectionable, as for example, in tires of what may be termed semi-solid character, adapted for heavy trucks and similar vehicles.

Referring now to Fig. 19, a representation is given of a fragmentary portion of a tire embodying constituent elements hereinbefore described. The rubber impregnated or treated rawhide forms the tread of the tire, the inner tube being constituted of the mercerized and rubber impregnated fabric which may be of single or multiple ply in cross section and coated inside and outside with rubber as the nature of the tire may require. In Fig. 20 a form of tire is shown in cross section, the tread portion, also of rubber-impregnated or treated rawhide, being internally connected with a lining of heavy fabric 6, contiguous to which is the mercerized rubber-saturated diagonally woven fabric, within which in

turn is the innermost tube similarly of heavy fabric 6. In Fig. 21 the same form of tread as that shown in Fig. 19 is found in which, however, the rubber-impregnated or treated rawhide is reinforced by a layer of mercerized rubber-impregnated fabric 4, while the interior of the tread tube is in contact with a tube of mercerized rubber-impregnated fabric between which and a similar innermost lining is interposed a layer of heavy fabric 6.

The fibrous material hereinbefore mentioned as mercerized is not specifically named, it being my intention to use any fabric of suitable character which is capable of mercerization. It is also to be understood that where rubber is mentioned rubber or rubber compounds of any form or character are intended to be included.

In Fig. 22 is shown a tubular formation, such as an inner tube of a tire, a fire hose or the like to the manufacture of which my article of manufacture is adaptable. It is also applicable to the purposes of insulation, and in the manufacture of shoe soles, life preservers, rain coats, medical mattresses, air cushions, collapsible boats, and in fact to a great variety of uses.

I claim:—

1. The herein described article of manufacture, the same consisting in a woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, substantially as set forth.

2. The herein described article of manufacture, the same consisting in a diagonally and reversely woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, substantially as set forth.

3. The herein described article of manufacture, the same consisting in a woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed

fibers, the rubber being vulcanized, substantially as set forth.

4. The herein described article of manufacture, the same consisting in a diagonally and reversely woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, the rubber being vulcanized, substantially as set forth.

5. The herein described article of manufacture, the same consisting in a woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, such rubber treated fabric being combined with a body formed of fragmentary, granulated or macerated rawhide impregnated with rubber, the said rubber treated fabric and rawhide being consolidated, substantially as set forth.

6. The herein described article of manufacture, the same consisting in a woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, such rubber treated fabric being combined with a body formed of fragmentary, granulated or macerated rawhide impregnated with rubber, the said rubber treated fabric and rawhide being consolidated, and the rubber entering into the fabric and rawhide being vulcanized, substantially as set forth.

7. The herein described article of manufacture, the same consisting in a diagonally and reversely woven mercerized fabric in

which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, such rubber treated fabric being combined with a body formed of fragmentary, granulated or macerated rawhide impregnated with rubber, the said rubber treated fabric and rawhide being consolidated, substantially as set forth.

8. The herein described article of manufacture, the same consisting in a diagonally and reversely woven mercerized fabric in which throughout the entire pattern a series of warps pass indirectly from its face to its back and in so passing interlace by engaging with and partly encircling intervening wefts within the body of the fabric, combined with rubber admitted to the interior and coated upon the exterior of each fiber and filling the spaces existing between the juxtaposed fibers, such rubber treated fabric being combined with a body formed of fragmentary, granulated or macerated rawhide impregnated with rubber, the said rubber treated fabric and rawhide being consolidated and the rubber entering into the fabric and rawhide being vulcanized, substantially as set forth.

9. The herein described article of manufacture, the same comprising a woven mercerized fabric in which throughout its entire extent a series of warp threads pass alternately and indirectly from one face to the other, each of said threads between its appearance on opposite faces passing around and interlacing with weft threads in the interior of the fabric, combined with rubber which is admitted in a soluble condition to the interior of each fiber so as to fill the bore thereof, coats the exterior of the fiber, and fills the spaces existing between the various fibers.

In testimony whereof I affix my signature in presence of two witnesses.

ALBERT H. HENDERSON.
